UNITED STATES PATENT OFFICE.

JOHN G. LANE AND GEORGE LANE, OF POUGHKEEPSIE, NEW YORK.

DESIGN FOR A NUT.

SPECIFICATION forming part of Design No. 23,917, dated December 25, 1894.

Application filed November 6, 1894. Serial No. 523,092. Term of patent 14 years.

To all whom it may concern:

Be it known that we, JOHN G. LANE and GEORGE LANE, both of Poughkeepsie, in the county of Dutchess and State of New York, 5 have invented a new and original Design for a Nut, of which the following is a full, clear, and exact description.

Reference is to be had to the accompanying drawings forming a part of this specification.

10 Figure 1 is an inverted plan view of a nut embodying our new design; and Fig. 2 is a side view thereof.

15 The leading feature of our design consists in a nut having the two parallel ornamental flanges shown, the lines of which depart laterally from the body at the bottom and near

the top respectively and present each a many armed figure.

The minor features of the design consist in the cylindrical body, and the ornamental 20 arms of one flange extending outward slightly beyond those of the other flange. The arms of one flange further overlap at one side the arms on the other flange as viewed in plan.

We claim—

25 The design for a nut herein shown and described.

JOHN G. LANE.
GEORGE LANE.
